UNITED STATES PATENT OFFICE

133,692

DESIGN FOR A CLASP

Barbara Beach, San Francisco, Calif.

Application November 19, 1940, Serial No. 96,680

Term of patent 3½ years

To all whom it may concern:

Be it known that I, Barbara Beach, a citizen of the United States, residing at 2929 Pierce Street, in the city and county of San Francisco, in the State of California, have invented a new, original, and ornamental Design for a Clasp, of which the following is a specification, reference being had to the accompanying drawing, forming a part thereof.

I claim:

The ornamental design for a clasp, substantially as shown.

BARBARA BEACH.
